COMPRESSOR

Ralph J. Kuntz, Columbus, Ohio

Application December 13, 1945, Serial No. 634,712

13 Claims. (Cl. 230—217)

1

My invention relates to a compressor. It has to do, more particularly, with a compressor which is especially suitable for use on an internal combustion engine for the purpose of compressing the gaseous fuel mixture before it enters the cylinders. However, my compressor can be adapted to other automotive uses, for refrigeration apparatus, and for many other purposes.

There is a need for a simple, small, compact and relatively light compressor which will function efficiently and effectively to compress a charge of fluid. This need is particularly evident in the automotive field, but is not limited thereto. For example, on large trucks or other vehicles it is desirable to increase the power of the internal combustion engine to facilitate travel up a grade or pulling of a heavy load at a reasonable rate of speed or to enhance the operation of the engine under other power-dissipating conditions.

One of the objects of my invention is to provide a simple, small, compact and relatively light compressor of the general type indicated which can be manufactured at a low cost.

Another object of my invention is to provide a compressor of the type indicated in the preceding paragraph which will function efficiently and effectively to compress a charge of fluid.

Another object of my invention is to provide a compressor which is particularly useful in association with an internal combustion engine for the purpose of compressing the gaseous fuel mixture before it enters the cylinders, thereby, increasing the power of the engine and resulting in a considerable saving of fuel.

Another object of my invention is to provide a compressor of such a nature that it can be readily associated with the carburetor of an internal combustion engine, will be automatic in operation, and will efficiently operate under all weather and atmospheric conditions.

Still another object of my invention is to provide a compressor of such a nature that it may be mounted on an internal combustion engine with ease and by the use of simple and inexpensive fixtures.

Various other objects will be apparent from the following description.

In the drawings referred to in the following descriptions, I have illustrated my compressor disposed in association with an internal combustion engine. However, it is to be understood that it is capable of other applications.

In associating it with an internal combustion engine, it is arranged so that it receives the gaseous fuel and air mixture from the carburetor,

2

compresses it, and then delivers it to the cylinders of the engine. A simple adapter is associated with the carburetor for connecting the intake line of the compressor to the carburetor and the outlet line of the compressor to the intake manifold of the engine. The compressor is preferably driven by the fan belt of the engine.

The compressor itself includes a hollow rotatable shaft which is driven by the fan belt. This shaft is connected by a suitable suction conduit to the carburetor and receives the fuel charge from the carburetor. The shaft carries a sleeve, within which it can rotate, and this sleeve carries disk-like pistons which do not rotate relative to the sleeve but can be reciprocated relative to the axis thereof. The pistons are arranged in pairs and the pistons of each pair are moved towards and away from each other. The pistons have their peripheral edges in close contact with a surrounding cylinder wall so that an annular fluid chamber is formed between each pair of pistons and between each end piston and the heads of the cylinder. The pistons are slidably carried on the sleeve and are secured thereto by means of pins which extend through longitudinal slots formed therein and which extend into cam grooves which are formed in the periphery of the hollow shaft. When the shaft is rotated, the sleeve, which is keyed in the heads of the cylinder, remains stationary, and the disk pistons are, consequently, reciprocated back and forth on the sleeve without being rotated. The cam grooves are so shaped that each pair of pistons will alternately move towards and away from each other. Thus, the annular chamber between each pair of pistons and the annular chamber at each end of the cylinder will alternately be a compression and a suction chamber.

The hollow shaft is provided with inlet ports in its peripheral wall which are so shaped that during rotation of the shaft within the sleeve, the ports at intervals are brought into and out of association with the key slots, formed in the sleeve, to permit the fuel charge to be drawn from the hollow shaft into each of the annular chambers and to be trapped therein. The inlet port of each chamber is closed before the compressing action, caused by movement of the pistons, occurs and is opened by the time the pistons move to create a suction force in the chamber. When the fluid charge in each chamber is compressed to a selected degree, an outlet valve in the wall of the cylinder automatically opens and allows the compressed charge to pass into an annular discharge chamber which

surrounds the cylinder. The chamber is connected by a suitable conduit to the intake manifold of the engine. Thus, a compressed charge is supplied to the engine.

The preferred embodiment of my invention is illustrated in the accompanying drawings wherein similar characters of reference designate corresponding parts and wherein:

Figure 1 is a perspective view, partly broken away, of a compressor constructed according to my invention.

Figure 2 is a side elevational view, partly broken away, of the compressor.

Figure 3 is a transverse sectional view taken substantially along line 3—3 of Figure 2.

Figure 4 is a view, in longitudinal section, of the upper portion of the compressor illustrating the passage of the charge into and out of the annular fluid chambers.

Figure 5 is a horizontal sectional view taken through the compressor.

Figure 6 is a transverse sectional view taken along line 6—6 of Figure 5.

Figure 7 is a diagrammatic view illustrating the successive steps in the operation of the compressor.

Figure 8 is a perspective view of the hollow shaft.

Figure 9 is a detailed view, mainly in section, of the adapter for use in connecting the compressor to the carburetor and to the intake manifold of an internal combustion engine.

Figure 10 is a perspective view showing the compressor associated with an internal combustion engine.

Figure 11 is a perspective view of the adapter showing the suction and pressure conduits connected thereto.

With reference to the drawings, in Figure 10 I have illustrated my compressor 1 associated with an internal combustion engine 2. It receives the gaseous fuel and air mixture from the carburetor 3, compresses it, and then delivers it to the intake manifold 4 which conducts it to the cylinders of the engine. A simple adapter 5 is interposed between the carburetor 3 and the intake manifold 4 for connecting the intake or suction line 6 of the compressor to the carburetor and for connecting the outlet or pressure line 7 of the compressor to the intake manifold 4. It will be noted that the compressor is mounted on the forward portion of the engine so that the fan belt 8 may pass around and drive the pulley 9 of the compressor. The compressor may be attached to the engine by suitable brackets (not shown) which may be secured to the compressor and the engine block by bolts or in any other suitable manner.

The adapted 5 is illustrated in Figures 9 and 11. It is in the form of a tubular housing which has a flange 10 on its upper end to which the carburetor flange is bolted and a flange 11 on its lower end which is bolted to the top surface of the intake manifold 4. The interior of the adapter 5 is divided into a suction chamber 12 and a pressure chamber 13 by means of an angularly disposed partition 14. A tubular boss 15 is provided on the adapter 5 and provides an outlet passageway for the chamber 12. This boss 15 will receive the end of the flexible conduit 6. A similar boss 16 provides an inlet passageway for the chamber 13 and receives the end of the flexible conduit 7. The end of the compressor 1 is provided with an inlet fitting 17 which receives the other end of the conduit 6 and is provided, intermediate its

ends and on its top surface, with an outlet tube 18 which receives the other end of the conduit 7.

The general structure of the compressor is illustrated best in Figures 1, 2, and 3. It is mainly of cylindrical form and includes an outer tubular shell 19 and an inner tubular shell 20 of slightly less diameter than the shell 19. At one end of the compressor a cylinder head 21 is provided and at the other end a cylinder head 22 is provided. The head 21 is of disk-like form and is provided with a reduced disk-like portion 23 on its inner surface which tightly fits within the shell 20 and closes the end of such shell. The member 21 overlaps a peripheral flange 24 on the end of the shell 19 and is tightly bolted thereto by means of the bolts 25. The head 22 is similar to the head 21 and is provided with a reduced portion 26 which fits within the shell 20 and a peripheral flange which is bolted to the peripheral flange 27 of shell 19 by means of bolts 28. Due to the fact that the shell 20 is smaller in diameter than the shell 19, an annular chamber 29 is formed. This chamber, as will later appear, will serve as an outlet chamber for the compressed fuel. The tubular outlet 18, which is formed on the shell 19, will lead from this chamber.

Rotatably mounted within centrally disposed openings in each of the heads 21 and 22 is a hollow shaft 30. This shaft is carried by a ball bearing 31 in the head 21 and a ball bearing 32 in the head 22. The ball bearing 31 is maintained in the bearing cup in the head 21 by means of the fitting 17 which is provided with a peripheral flange 33 that is bolted by means of bolts 34 to a boss 35 formed on the head. The end of the shaft 30 terminates within the flange 33 of the fitting 17. The opposite end of the shaft extends a considerable distance outwardly beyond the head 22 and carries the driving pulley 9 which is keyed thereto. A collar 36 is bolted by means of bolts 37 to a boss 38 formed on the head 22. This collar closely surrounds the extension of shaft 30 and maintains the bearing 32 in position within the cup formed in the head 22.

As previously stated, the fitting 17 provides an inlet for the compressor. This fitting communicates with the adjacent end of the hollow shaft 30, as shown best in Figure 2. The opposite end of the shaft is closed by means of a plug 39 which is fitted tightly therewithin. The shaft 30 is provided with a series of outlet ports 40 which are of special shape and are located in selected positions. These ports 40 will be referred to more in detail hereinafter.

Closely surrounding the shaft 30, between the heads 21 and 22, is a sleeve 41. This sleeve has its ends extending into the central openings of the heads 21 and 22 and the ends are keyed therein to prevent rotation of the sleeve. The portion of the shaft 30 which is disposed between the heads 21 and 22 is enlarged and fits tightly within the sleeve 41. The sleeve 41 is provided with four pairs of diametrically opposed elongated slots 42 which extend completely therethrough. These slots extend longitudinally of the sleeve and are spaced longitudinally from each other. The slots on each side of the sleeve are in alignment.

Carried on the sleeve 41 are four disk-like pistons 43. These pistons are so mounted that they will not rotate on the sleeve but are free to move axially thereof. Each of the pistons 43 closely surrounds the sleeve 41 and its outer peripheral edge is in close, substantially fluid-tight contact with the inner surface of the shell 20. Each of

the pistons 43 carries at diametrically opposed points, within radially extending sockets, the plungers 44. Each plunger 44 includes a spring 45 which forces a pin 46 towards the axis of the sleeve 41. Each of the pins 46 extends through one of the slots 42 in the sleeve 41. This, consequently, will prevent the pistons 43 from rotating on the sleeve 41, but will permit axial movement of the pistons.

Each pair of diametrically opposed pins 46 extends into a cam groove 47 which is formed in the periphery of the hollow shaft 30. The cam grooves 47 are of the outline illustrated best in Figure 8. Each cam groove consists of two communicating substantially U-shape sections disposed on opposite sides of the shaft and extending in the same direction and to the same extent longitudinally of the shaft. Thus, when the shaft 30 rotates relative to the sleeve 41, the piston 43 will be moved back and forth axially of the sleeve 41 through two complete movements during a single rotation of the shaft. The slots 42 are so associated with the grooves 47 and are of sufficient length that the axial movement of the pistons is permitted without the pins 46 interfering with the ends of the slots.

The pistons 43 are arranged in two pairs disposed at opposite sides of the midpoint of the compressor. Consequently, four of the cam grooves 47 are provided. The adjacent cam grooves are oppositely disposed so that they approach each other as indicated in Figure 8. Consequently, when the shaft 30 rotates, the pistons 43 of each pair will move towards and away from each other. The end pistons will move towards and away from the cylinder heads with which they are associated. Thus, five annular chambers will be provided around the sleeve 41 within the shell 20 and these chambers will be alternately pressure chambers and suction chambers. In other words, there will be a charge-receiving chamber between the two innermost pistons, a charge-receiving chamber between each of the outer pistons and the adjacent inner pistons, and a charge-receiving chamber between each of the outer pistons and the adjacent cylinder head.

The shape of each of the inlet ports 40 and the location of these ports relative to the cam grooves 47 is illustrated best in Figure 8. Each of the ports 40 is of equilateral triangular outline with one of the vertices of the triangle being at the leading edge of the port, the hollow shaft being designed to rotate in a clockwise direction, as viewed from the front of the compressor in Figure 10. In addition to the ports 40, ports 40a are provided at the ends of the sleeve 41 and are of right triangular outline. Two of these ports 40 are provided at each end of the shaft at diametrically opposed points and each is so arranged that its side, which corresponds to the hypotenuse of the triangle, is parallel to the outer edge of the end cam groove 47. However, these sides of the two ports extend in opposite directions, one extending outwardly towards the end of the shaft and the other extending inwardly. The ports 40a at the opposite ends of the shaft are in alignment with each other, and between these end ports 40a, one of the ports 40 is disposed. This port 40 has its side edges parallel with the inner edges of the two inner cam grooves 47. Between the two longitudinal lines of ports 40 and 40a, just described, and spaced circumferentially thereof, a pair of the ports 40 are located in longitudinal alignment and spaced longitudinally from each other. Each of the ports 75

40 of these two pairs will have its side edges parallel with the inner edges of the two end cam grooves 47. The special arrangement of the ports 40 and 40a described above is for a purpose which will be apparent more clearly hereinafter. These ports, during rotation of shaft 30, will be brought into communication with the slots 42 formed in the sleeve 41. This will permit the fuel mixture to pass from the hollow shaft 30 into the annular charge-receiving chambers around the sleeve 41.

For permitting the fuel charge to escape from the various charge-receiving chambers after being compressed, I provide a series of outlet ports 48. Each of the ports 48 is controlled by a one-way check valve. Each check valve consists of a flat valve seat 49 which is secured to the exterior of the shell 20, as shown in Figures 1 to 4, and through which the outlet 48 extends. A flat leaf spring 50 is attached to the outer surface of the seat 49 and normally is seated on member 49 in closing relationship to the outlet 48. However, sufficient pressure developed within shell 20 will bend the leaf spring 50 and unseat it from the outlet opening, permitting escape of the compressed charge through the shell 20 and into the outer annular chamber 29.

The outlet ports 48 are arranged in five longitudinally spaced rows so as to provide a row of these ports for each of the charge-receiving chambers. Each row consists of four of these ports, spaced circumferentially around the shell 20 at 90° intervals. The check valves of each row will all open and close simultaneously. Each row of check valves is so located longitudinally of the compressor that the ports 48 thereof will not be covered when the charge-receiving chamber with which they communicate is serving as a compression chamber. This will be evident from a comparison of Figures 2 and 4. Also, it will be noted from these figures that by the time the pistons have moved to compress a charge in a particular charge-receiving chamber, the inlet ports 40 or 40a which supplied the charge to said chamber will have been closed.

The operation of the compressor will be clear from reference to Figures 5, 6, and 7. When the internal combustion engine is started, the pulley 9 is driven in a clockwise direction thereby rotating the shaft 30 in a clockwise direction. The carburetor 3 will feed a charge of fuel into the conduit 6. Assuming the pistons 43 are in the 0-stage as shown at the left of Figure 7 with the two outer pistons moved outwardly to the extent of their movement and the two inner pistons moved together to the extent of their movement, the compressor will operate through four stages, during a single revolution of the shaft, which will automatically result upon continued rotation of the shaft 30. In the first stage (number 1 in Figure 7) the pair of inlet ports 40a at each side of the shaft 30 move into registry with the two end slots 42 on each of the diametrically opposed sides of the sleeve 41. Simultaneously the two diametrically opposed inlet ports 40, disposed between the end ports 40a, move into registry with both pairs of the diametrically opposed slots 42 disposed adjacent to the central portion of the sleeve. Due to the shape of the ports 40 and 40a, there is a gradual registration of the ports with the slots. This provides for a gradual smooth feed of the fuel charge from the hollow shaft into the charge-receiving chambers. Also, in this first stage, the pistons of each pair are moved towards each other. During this move-

ment, the fuel charge will be sucked in from the hollow shaft through the exposed openings 40 and 40a since relative rotation of the shaft 30 and sleeve 41 not only moves the pistons 43, but also controls the ports 40 and 40a. Thus, in this stage, the two chambers at the end of the compressor will serve as suction chambers and the fuel charges will be drawn thereinto through the ports 40a. The middle chamber will also serve as a suction chamber and the fuel charge will be drawn thereinto through the port 40. The chambers between the pistons of the two pairs of pistons, in this stage, will serve as compression chambers which have previously received charges of fuel. These charges will be compressed as the pistons of each pair move together and as they reach the extent of their movement, the valves 50 for that chamber will open permitting the compressed charge to flow through the outlets 48.

In the second stage (numbered 2 in Figure 7), the two pairs of pistons are moved in such a manner that the pistons of each pair move away from each other. This results in the two end chambers and the middle chamber becoming compression chambers and in the chamber between each pair of pistons becoming a suction chamber. Simultaneously with such movement of the pistons, certain of the ports 40 are exposed, allowing the fuel charges to be drawn into the suction chambers. The compressed fuel from the three compression chambers of this stage will be forced from such chambers through the outlets 48 provided therefor.

The next two stages (numbered 3 and 4 in Figure 7) which occur during the single rotation of the shaft are exactly the same as stages 1 and 2.

The movement of the pistons will increase and decrease in accordance with the increase and decrease of the revolutions per minute of the internal combustion engine. Thus, the amount of compressed fuel supplied to the engine will be gauged according to the requirements of the engine. The compressed fuel will be supplied from the various compression chambers successively and at frequent intervals so that sufficient pressure will be built up within the annular outlet chamber 29, the conduit 1 and the intake manifold 4.

It will be apparent from the above description that I have provided a simple, small, compact, relatively light and low cost compressor. However, it is of such a nature that it will function efficiently and effectively to compress a charge of fluid. My compressor is particularly useful in association with an internal combustion engine for the purpose of compressing the gaseous fuel mixture before it enters the cylinders, thereby, increasing the power of the engine and resulting in a considerable saving of fuel. The compressor is of such a nature that it can be associated readily with the carburetor of an internal combustion engine, it will be automatic in operation and will operate efficiently under all weather and atmospheric conditions. The compressor is of such a nature that it may be mounted on an internal combustion engine with ease by the use of simple and inexpensive fixtures.

Having thus described my invention, what I claim is:

1. A compressor comprising a shell, a hollow shaft extending within said shell and being rotatably mounted therein, pistons disposed within said shell and being non-rotatably but reciprocably mounted relative to said shaft, means for re-

ciprocating said pistons relative to said shaft upon rotation of said shaft, said shaft being provided with inlet ports in its wall for permitting fluid to enter the space within said shell, a second shell enclosing the first shell to provide an outlet chamber therearound, and pressure-responsive valves for controlling the passage of fluid from within said first shell to the outlet chamber.

2. A compressor according to claim 1 wherein the first shell is provided with a plurality of outlet ports controlled by said valves, said valves being one-way check valves.

3. A compressor comprising a shell, a hollow shaft extending within said shell and being rotatably mounted therein pistons disposed within said shell and being non-rotatably but reciprocably mounted relative to said shaft, said pistons being disposed in pairs, means for causing the pistons of each pair to move towards and away from each other upon rotation of said shaft, said shaft being provided with inlet ports in its wall for permitting fluid to enter into the chambers formed around said shaft within said shell, a second shell enclosing the first shell to provide an outlet chamber therearound, and pressure-responsive valves for controlling the passage of fluid from said chambers into said outlet chamber.

4. A compressor comprising a shell, a hollow shaft within said shell and being rotatably mounted therein, a sleeve disposed within said shell and being non-rotatably mounted therein in surrounding relationship to said shaft, pistons disposed within said shell and mounted on said sleeve for axial but non-rotatable movement relative thereto, said sleeve and said hollow shaft being provided with inlet ports adapted to be brought into and out of registration during rotation of said shaft, means for moving said pistons axially of said sleeve upon rotation of said shaft, a second shell enclosing the first shell to provide an outlet chamber therearound, and pressure-responsive valves for controlling the passage of fluid from within said first shell to the outlet chamber.

5. A compressor according to claim 4 wherein said pistons are splined to the sleeve by means of pins carried by the pistons and extending through longitudinally extending slots formed in said sleeve, said means for moving said pistons axially of said sleeve comprising cam grooves formed in said shaft and into which said pins extend.

6. A compressor comprising a shell, a hollow shaft within said shell and being rotatably mounted therein, a sleeve disposed within said shell and being non-rotatably mounted therein in surrounding relationship to said shaft, pistons disposed within said shell and being mounted in pairs on said sleeve for axial but non-rotatable movement relative thereto, said sleeve and said hollow shaft being provided with inlet ports adapted to be brought into and out of registration during rotation of said shaft, means for moving the pistons of each of said pairs towards and away from each other axially of said sleeve upon rotation of said shaft, each of said pistons carrying pins which extend through longitudinally extending slots formed in said sleeve, said means for moving the pistons comprising cam grooves extending around the shaft and within which said pins extend, a second shell enclosing the first shell to provide an outlet chamber therearound, and pressure-responsive valves for controlling the passage of fluid from within said first shell to the outlet chamber.

7. A compressor according to claim 6 wherein the first shell is provided with a plurality of outlet ports controlled by said valves and arranged in longitudinally spaced circumferentially extending rows, said valves being one-way check valves.

8. A compressor comprising a shell, a hollow shaft within said shell and being rotatably mounted therein a sleeve disposed within said shell and being non-rotatably mounted therein in surrounding relationship to said shaft, disk-like pistons disposed within said shell and being mounted in pairs on said sleeve for axial but non-rotatable movement relative thereto, said sleeve being provided with longitudinally extending slots and said hollow shaft being provided with inlet ports which are adapted to be brought into and out of registration during rotation of said shaft, means for moving the pistons of each of said pairs towards and away from each other axially of said sleeve upon rotation of said shaft, said means including radially extending pins carried by said pistons which extend through said slots formed in said sleeve, cam grooves extending around the shaft into which said pins extend, a second shell enclosing the first shell to provide an outlet chamber therearound, and pressure-responsive valves for controlling the passage of fluid from within said first shell to the outlet chamber.

9. A compressor according to claim 8 wherein said pins carried by said pistons are urged radially inwardly into said cam grooves by springs carried by the pistons and associated with the pins.

10. A compressor comprising a casing, a hollow shaft extending within said casing and being rotatably mounted therein, a sleeve disposed within said casing and being non-rotatably mounted therein in surrounding relationship to said shaft, pistons disposed within said casing and being mounted on said sleeve for axial but non-rotatable movement relative thereto, said sleeve and said hollow shaft being provided with inlet ports adapted to be brought into and out of registration during rotation of said shaft, means for moving said pistons axially on said sleeve upon

rotation of said shaft, and pressure-responsive means for controlling the passage of fluid from said casing.

11. A compressor according to claim 10 wherein said pistons are splined to the sleeve by means of pins carried by the pistons and extending through longitudinal slots formed in said sleeve, said means for moving said pistons axially of said sleeve including cam grooves formed in said shaft and into which said pins extend.

12. A compressor comprising a casing, a hollow shaft extending within said casing and being rotatably mounted therein, a sleeve disposed within said casing and being non-rotatably mounted therein in surrounding relationship to said shaft, pistons disposed within said casing and being mounted in pairs on said sleeve for axial but non-rotatable movement relative thereto, said sleeve being provided with longitudinally extending slots and said hollow shaft being provided with inlet ports which are adapted to be brought into and out of registration during rotation of said shaft, means for moving the pistons of each of said pairs towards and away from each other axially of said sleeve upon rotation of said shaft, said means including radially extending pins carried by said pistons which extend through said slot formed in said sleeve, cam grooves extending around the shaft into which said pins extend, and pressure-responsive valves for controlling the passage of fluid from said casing.

13. A compressor according to claim 12 wherein said pins carried by said pistons are urged radially inwardly into said cam grooves by springs carried by the pistons and associated with the pins.

RALPH J. KUNTZ.
